UNITED STATES PATENT OFFICE.

ALFRED A. LANTERNIER, OF LIMOGES, FRANCE.

DESIGN FOR A COVERED DISH.

SPECIFICATION forming part of Design No. 24,984, dated December 17, 1895.

Application filed May 14, 1895. Serial No. 549,325. Term of patent 7 years.

to all whom it may concern:

Be it known that I, ALFRED A. LANTERNIER, a citizen of the Republic of France, residing at Limoges, France, have invented and produced a new and original Design for a Dish, of which the following is a specification.

The leading features of my design consist of a dish of essentially the shape and surface configuration or pattern shown and described, wherein—

Figure 1 illustrates a side view of a dish embodying my design. Fig. 2 shows a top or plan view of the same. Fig. 3 is a top view in outline showing the contour of the body of a dish embodying my design.

In the drawings, A represents the body of the dish, the edge of whose flanged base B is serrated near the ends, as at a. The sides of

the body portion of the dish present ornamental ovaloid panels b, each of which extends at one end nearer to one end of the dish than at the other, the mouth of the dish following the general contour of said panels.

The cover C of the dish is substantially ovaloid in outline, and tapers in irregular undulations x to its edge throughout the entire circumference thereof. A handle d projects from the top of the cover.

What I claim is—

The design for a dish, substantially as shown and described.

ALFRED A. LANTERNIER.
